PERCY M. FOWL, HENRY R. KRUEGER, CHARLES E. FRENCH, AND FRED J. HEIDEMAN,
ALL OF DETROIT, MICHIGAN.

THERMOSTAT.

1,336,518.

Specification of Letters Patent. Patented Apr. 13, 1920.

Application filed March 14, 1919. Serial No. 282,549.

To all whom it may concern:

Be it known that I, FRED J. HEIDEMAN, a citizen of the United States, residing at Detroit, in the county of Wayne and State of Michigan, have invented a new and useful 5 Thermostat, of which the following is a specification.

This invention relates to thermostats and more particularly to thermostats of the type 10 depending upon the varying volume of a liquid at different temperatures to exercise control of an electric circuit.

It is the object of the invention to provide a thermostat having a particular application 15 to automatic refrigerating plants, although not limited to such application, which thermostat is arranged to open and close an electric switch upon a predetermined variation of temperature, and is quickly adjustable to vary the extent to which the temperature must rise or fall to effect a closing 20 or opening of the switch.

Furthermore, it is an object of the invention to cause the opening or closing of the 25 switch to take place upon a definite degree of movement of the thermostat regardless of any adjustment varying the responsiveness of the device to temperature conditions.

A preferred embodiment of the invention 30 is illustrated in the accompanying drawing wherein:

Figure 1 is a vertical sectional view of the invention, a portion of the switch casting being omitted to disclose the mechanism 35 of the switch.

Fig. 2 shows the thermostat in side elevation.

Fig. 3 is a top view of the thermostat.

Fig. 4 is a sectional view of a detail of 40 the operating mechanism, the section being taken on line 4—4 of Fig. 3.

In these views the reference characters 1 and 2 respectively designate the bottom and top plates of a frame or stand which carries 45 the thermostatic mechanism, said plates being rigidly connected by bolts 3 passing through spacer sleeves 4, interposed between peripheral portions of said plates. These plates are of a spider construction, allowing 50 a free circulation of air against the ends of the sylphon 5, arranged between said plates, and the bottom plate is formed with feet 6 adjacent its periphery to space it

above any supporting surface, as for example a shelf within a refrigerator. The 55 sylphon 5 is of the ordinary corrugated expansible tubular construction and is closed at its lower end by the plate 7 which is secured to the bottom member of the frame in any suitable manner. 60

The top surface of the plate 1 may be slightly recessed as indicated at 7^a to allow said plate 7 to seat flush with the top of the plate 1. As a preferred means for holding the plates 1 and 7 in fixed relation there is 65 employed a bushing 8 passing centrally through said plates and having on its upper end the annular flange 9 bearing upon the plate 7. The plate 1 is formed with a depending boss 10 to give more adequate retention to said bushing, the latter being rigidly held in said boss by any suitable means, as for example, welding. The upper end of the sylphon is closed by the plate 11, 70 cupped or recessed in its center portion as 75 is indicated at 12 in Fig. 1. The sylphon is supplied, as is usual, with some fluid having a relatively large coefficient of expansion, as for example, sulfur dioxid. The central opening 13 of the bushing 8 permits of 80 filling the sylphon with the expansible liquid, said opening normally being sealed by a valve 14 which may be in the nature of an ordinary screw.

In the upper end plate 11 of the sylphon 85 there is centrally screw-threaded the lower end of a post 15 which passes slidably through a bearing provided by a nut 16 engaging a central aperture in the plate 2. Between said nut and the upper end plate 11 90 of the sylphon there is engaged a coiled spring 17, the compression of which may be regulated by adjusting said nut. Above the nut 16 the post 15 intermediately engages a lever 18 which, upon being swung through 95 a slight angle, is adapted to actuate a snap switch 19 to open or close an electric circuit 19^a. The mechanism of said switch being quite common is illustrated only in a general way, 20 and 21 being a pair of spring 100 contacts, and 22 a contact pivoted between the members 20 and 21, and actuatable by means of a reciprocatory rod 23 to either bridge the gap between the contacts 20 and 21 or to maintain the spaced relation to both 105 of said contacts shown in Fig. 1, said mech-

anism being mounted within the two-part insulator casing 24, which is carried by the bracket 25 mounted fast upon the plate 2.

To reciprocate the rod 23 through swing-
5 ing of the lever 18, the latter is terminally formed with a yoke 26 which engages an annularly grooved collar 27 upon the lower end of said rod.

The fulcrum of the lever 18 is indicated at
10 28. It is desirable to avoid any appreciable movement of the rod 23 when the nut 16 is adjusted to vary compression of the spring 17, and since the end plate 11, which carries the post 15, tends to shift upwardly or down-
15 wardly whenever the compression of the spring is decreased or increased, it is necessary to secure a substantially equal and corresponding movement of the lever fulcrum to prevent shifting of the rod 23. The desired
20 result is achieved by mounting the fulcrum of the lever upon the adjusting nut 16, the mounting being such as to allow the fulcrum to move vertically with the nut without rotating therewith. Thus the lever is ful-
25 crumed upon the head portion of a screw 28 laterally projecting from the cylindrical sup-
port 29 slidably mounted in the slotted sleeve 30 carried by an arm 31 projecting from the bracket 25. Through the slot 32 of said
30 sleeve the screw 28 projects. The lower end portion of the member 29 is engaged by the adjusting screw 33 which has its head 34 disposed within an annular groove 35 jointly formed by the nut 16 and by a ring 36
35 screw-threaded upon said nut. A collar upon the screw 33 for adjusting the same is indicated at 37.

Discussing briefly the operation of the above-described device, it is evident that ex-
40 pansion of the sylphon is resisted by the coiled spring 17 and that expansion or con-
traction of the sylphon through a predeter-
mined extent will act upon the switch 19 to make or break the circuit 19^a.

45 The necessary degree of expansion or con-
traction of the thermostat to effect a snap actuation of the switch will take place upon a relatively slight variation in temperature if the spring is under slight compression, any
50 increase in the degree of compression of the spring resulting in a corresponding increase in the temperature range, at the limits of which the switch is actuated. Thus regu-
55 lation of the compression of the spring 17 by means of the nut 16 affords an accurate control of the thermostat with respect to the temperature limits at which opening or clos-
60 ing of the electric circuit 19^a takes place. By mounting the fulcrum of the lever 18 upon the adjusting nut, any inaccuracy due to shifting of the switch rod 23 upon adjust-
ment of the nut 16 is substantially avoided.

However, in case any slight shifting of said rod should occur, owing perhaps to a shortening or lengthening of the spring 17 upon 65 adjustment of the nut 16, the screw 33 may be turned to shift the lever fulcrum slightly up or down so as to return the rod 23 to its proper normal position.

Circuit closing means other than that 70 shown might of course be similarly controlled by the disclosed thermostatic mechanism, and the other feature of the invention might be variously modified within the scope of the accompanying claims. 75

What I claim is:

1. In a thermostat, the combination with the heat-responsive element thereof, of an electric switch, a lever for actuating said switch from the heat-responsive element, a 80 spring opposing expansion of the heat-responsive member, an abutment for said spring adjustable to vary the compression thereof, a fulcrum for said lever, and means constraining said fulcrum to follow said abutment when the latter is adjusted.

2. In a thermostat, the combination with the heat-responsive element thereof, of an electric switch, a lever for actuating said switch, a rod for actuating the lever from 90 said heat-responsive element, a spring opposing expansion of the heat-responsive element, an abutment for said spring adjustable to vary the compression thereof, said abutment forming a slide bearing for said rod, a fulcrum for said lever, and means constraining said fulcrum to follow said abutment when the latter is adjusted. 95

3. In a thermostat, the combination with the heat-responsive element thereof, of an 100 electric switch, a lever for actuating said switch from the heat-responsive element, a spring opposing expansion of the heat-responsive element, an abutment for said spring adjustable to and from the heat-responsive 105 element to vary the compression of the spring, a fulcrum for said lever constrained to follow said abutment when the latter is adjusted, and means for adjusting said fulcrum with relation to the abutment. 110

4. In a thermostat, the combination with a frame comprising spaced plates, of a sylphon arranged between said plates, a bushing securing one end of the sylphon to one of said plates of the frame, the passage 115 in said bushing forming a fill opening for the sylphon, a valve seated in said bushing normally closing the opening thereof, a switch carried by the other plate of said frame, and means for actuating said switch 120 from the sylphon.

In testimony whereof I sign this specification.

FRED J. HEIDEMAN.
